ADJUSTABLE-CAN-TRACK COOKER

Albert R. Thompson, San Jose, Calif., assignor to
 Food Machinery Corporation, San Jose, Calif.,
 a corporation of Delaware

Application January 26, 1932, Serial No. 589,029

17 Claims. (Cl. 198—211)

The present invention relates to that class of cookers and other apparatus for treating canned goods in which the cans are propelled around a helical track by an interior revolving reel having a plurality of longitudinally disposed pusher bars.

One object of the invention is to provide means for adjustably supporting the can track or helix in order to establish and maintain its proper concentric alignment with respect to the revolving reel within it. Cookers of this type are frequently made as long as thirty feet with a diameter of about five feet, and in machines of such dimensions it has been found difficult to maintain correct alignment between the helix and the reel. If the space between the helical can track and the pusher bars of the reel is too small at any particular point, the bars will bind against the track, and if the space is too great, one or more cans may jump either the track or the reel bar, thereby jamming and causing a serious delay in the operation of the machine. It is especially important to maintain accurate alignment in machines which are used for cans of more than one diameter, as is frequently done; when such a machine is operating upon cans of the smallest size for which it is designed, faulty alignment of the helix of only one quarter of an inch may cause a can to jump and jam.

Another object of the invention is to reduce the interior space established in the lower portion of the cooker, which is customarily partially filled with hot water, thereby conserving both water and heat. A third object is to provide the maximum rigidity with minimum weight. A still further object is to provide a machine from which the helix of the reel can be removed from the top, for necessary repair or replacement, thereby saving floor space, over the usual machines which are so constructed that the reel must be removed from one end. The last three objects above enumerated are achieved by constructing the shell or tank of the cooker with a round or semi-cylindrical bottom, and a rectangular or flat top. The flat top also provides convenient access to the interior for cleaning and minor repairs.

Other objects and advantages of the invention will become apparent from the following description of a preferred form thereof, which should be read with the understanding that changes, within the limits of the claims hereto appended, may be made in the form, construction, and arrangements of the several parts.

Reference will be made to the accompanying drawing in which

Fig. 1 is a transverse section of my cooker.

Fig. 2 is a vertical longitudinal section of one end portion thereof.

Fig. 3 is a detailed plan, enlarged, of a portion of the bottom of the helix and tank, showing one of the bottom helix adjusting members.

Fig. 4 is a broken side elevation, on a reduced scale, of the tank.

In the drawing, the reference numeral 1 designates a shell or tank having a semicylindrical bottom and a rectangular flat top closed by a suitable removable cover 2. Ends 3, one of which is shown in Fig. 2, complete the tank. Suitable cradles 4 support the tank, and because of the rigidity inherent in the semicylindrical lower portion, it is usually necessary to employ only two such cradles, as indicated in Fig. 4, the ends of the tank being cantilevered beyond said cradles.

Within the tank is a helical can track formed from a rail 5 of T-section. The helix is held together, to preserve proper spacing between its adjacent convolutions, by a plurality of longitudinally disposed angle bars 6, there being preferably six such bars, as shown in Fig. 1. The helix is suspended within the tank by means of adjustable hangers 7, which are hooked or otherwise secured to certain of the longitudinal angle bars 6. The hangers 7 extend through brackets 8 secured to the interior side walls of the tank, and are provided with nuts 9 above said brackets.

Lateral adjustment of the helix is provided by connections with the side walls of the tank. For this purpose the helix is provided with longitudinal bars 10, through which extend bolts 11, the ends of said bolts passing through the side walls of the tank. The heads of the bolts lie inside the bars 10 between the T-rails of the helix. Nuts 12 are threaded upon the bolts immediately outside said bars, and nuts 13 are also threaded upon the bolts inside and outside of the wall of the tank. The holes through which the bolts extend, either in the bars 10 or the wall of the tank, or both, are preferably larger than the bolts to allow sufficient play to permit vertical adjustment of the helix when the nuts 12 and 13 are loosened.

Lateral adjustment of the lower portion of the helix is provided by the following means. In the bottom of the tank, approximately along its center line, are a number of interiorly threaded bushings, one of which is shown at 14, in Figs. 1 and 3. A stud 15 is screwed through each of said bushings, and is provided with a wrench receiving head on its outer end, and an eccentrically dis-

posed pin 16 on its inner end. The pin 16 rests within a groove or channel 17 formed upon the bottom longitudinal angle bar of the helix, so that turning the stud will shift the lower portion of the helix laterally. A lock nut 18 is provided upon the stud to lock it in adjusted position and to prevent leakage of water around its threads.

The upper portions of the sides of the tank 10 are braced to each other and to the upper portion of the helix by transverse bolts 19 which extend through the top angle bar of said helix. Tubular spacers 20 surround said bolts between said angle bar and the sides of the tank.

15 The usual can propelling reel 21 is rotatably mounted within the helix and is provided with longitudinal pusher bars 22 for propelling the cans in the usual manner around the track formed by the helical T-rail. The ends of the reel 21 20 are journaled in suitable bearings 24, carried by frames 25 secured to the ends 3 of the tank. The ends of the longitudinal bars 6 of the helix are also secured to said frames 25, so that the helix is accurately centered at its ends about the axis 25 of the reel.

The reel is rotated and cans are fed into and discharged from the machine in the customary manner. Fig. 4 of the drawing shows a can entrance at 26 and can exit at 27. The tank is 30 customarily filled with water to about the level of the can exits 27, and said water is heated by steam pipes 28 preferably disposed longitudinally in the bottom of the tank between its wall and the helical rail 5. Auxiliary steam pipes 29 are 35 also positioned in the upper portion of the tank.

The hangers and lateral adjusting connections of the helix are preferably located about three or four feet apart in the length of the tank, as indicated in Fig. 4. After the machine is assembled, 40 the hangers 7 are adjusted to provide the proper vertical clearance between the reel bars and the helical track; then the side bolts 11 and the bottom studs 15 are adjusted to provide the proper lateral clearance; and, finally, the transverse bolts 45 19 across the top of the tank are put in position with the spacers 20 of the proper length to hold the upper portion of the helix and the sides of the tank in correct lateral relation. By this means the helix can be accurately centered 50 throughout its entire length about the reel, so that its alignment is established and maintained.

It should be noted that because the helix is supported at frequent intervals in its length, it can be made of lighter material than would otherwise 55 be the case. This applies especially to the longitudinal bars 6, which can be not only lighter but smaller in width, so that the bottom of the tank can be brought closer to the can track, thereby reducing the space within the tank which must be supplied with water and heat.

60 It is also to be noted that the shape of the tank itself saves interior space because of its semicylindrical lower portion. The semicylindrical form of the lower portion of the tank, moreover, 65 greatly increases its rigidity, and permits lighter material to be used. The rectangular upper portion of the tank, closed only by the removable cover 2, permits the entire helix and reel to be removed from the top of the tank, instead of 70 requiring that they be removed from the end as is customary in cylindrical cookers. This effects a saving in floor space by permitting the machine to be placed closer together.

I claim:—

75 1. A cooker comprising a tank; a rotating can

propelling reel therewithin; bearing members for supporting said reel at its ends; a can track member surrounding said reel, said track member being in the form of a continuous helix having its ends connected with said bearing members; and means for adjustably supporting said can track member intermediate its ends to center its intermediate portion about said reel.

2. A cooker comprising a tank; a rotating can propelling reel therewithin; a continuous helical can track member surrounding said reel; and connecting means between said track member and the walls of said tank for supporting said track member, said connecting means being adjustable to shift said track member bodily to center it about the axis of said reel.

3. A cooker comprising a tank; a rotating can propelling reel therewithin; a can track member surrounding said reel; means for adjustably suspending said track member from said tank; and other means for adjusting said track member laterally to align it about said reel.

4. A cooker comprising a tank; a rotating can propelling reel therewithin; a can track member supported within said tank and surrounding said reel; and means extending through the bottom of said tank and engaging said track member for laterally adjusting its position.

5. A cooker comprising a tank; a rotating can propelling reel therewithin; a can track member supported within said tank and surrounding said reel; a rotatable stud extending through a wall of said tank; and a pin eccentrically carried by said stud within said tank, said pin engaging said track member for moving it upon rotation of said stud.

6. A cooker comprising a tank; a rotating can propelling reel therewithin; a can track member supported within said tank and surrounding said reel; adjustable connections between the sides and bottom of said tank and said track member for shifting it laterally.

7. A cooker comprising a tank having an approximately semicylindrical bottom and sides extending vertically upward therefrom; a removable cover for closing the top of said tank; a can propelling reel rotatably mounted within said tank; a can track member surrounding said reel within said tank; and adjustable connections between the walls of the tank and said track member for shifting said track relatively to the axis of said reel.

8. A cooker comprising a tank having an approximately semicylindrical bottom and sides extending vertically upward therefrom; a removable cover for closing the top of said tank; a can propelling reel rotatably mounted within said tank; and a can track member surrounding said reel within said tank, said track member being supported by said tank for adjustment relative to the axis of said reel and removable through the top of said tank.

9. A cooker comprising a tank having side walls and a removable top; a can propelling reel rotatably mounted within said tank; a helical rail forming a can track surrounding said reel within said tank; longitudinal members connecting the convolutions of said rail together, one of said members being positioned at the top of said convolutions; and spacing means connecting said top longitudinal member with the sides of said tank.

10. A cooker comprising a tank; a can propelling reel rotatably mounted therewithin; a helical rail forming a can track surrounding said reel

within said tank; longitudinal members connecting the convolutions of said rail together; and means for adjustably connecting said longitudinal members with said tank for supporting said track and centering it about said reel.

11. A cooker comprising a tank; a rotatable can propelling reel therewithin; bearings supported by the ends of said tank for carrying said reel; a helical rail forming a can track surrounding said reel; longitudinal members connecting the convolutions of said rail together, the ends of said members being connected with the ends of the tank; and means adjustably connecting said members intermediate their ends with the sides of said tank.

12. A cooker comprising a tank; a rotatable can propelling reel therewithin; a helical can track member surrounding said reel; means for supporting said track member within the tank; and means for adjusting said track member both laterally and vertically with respect to said reel to align said track member about said reel.

13. A cooker comprising a tank; a rotatable can propelling reel therewithin; a continuous helical can track member having its ends supported in fixed position at the ends of the tank; and means for adjustably positioning the intermediate portion of the can track member to align it with the reel throughout its length.

30 14. A cooker comprising a tank; a rotatable can propelling reel therewithin; a helical can track member having its ends supported in fixed position at the ends of the tank; and means for adjustably positioning the intermediate portion

of the track member both laterally and vertically to align it with respect to the reel throughout its length.

15. A cooker comprising a tank having an open top; a removable cover therefor; a rotatable can propelling reel therewithin; a helical can track member surrounding said reel, said track member and said reel being removable bodily through the top of said tank; and means for adjusting the annular space between said reel and said track, while in said tank, to align them axially.

16. A cooker comprising a tank having an open top; a removable cover therefor; a rotatable can propelling reel therewithin; a helical can track member surrounding said reel, the ends of said track member being supported in fixed position at the ends of the tank, and said reel and said track member being removable bodily through the top of said tank; and means for adjustably positioning the intermediate portion of said track member to align it with said reel throughout its length.

17. In a cooker for canned goods, a helical can track; means connecting the convolutions thereof together to form an elongated continuous helical track structure; an elongated reel rotatably mounted within said track structure; pusher members carried by said reel for propelling the cans around said helical track; and means for flexing the longitudinal axis of said track structure to enable it to be centered accurately about said reel throughout its entire length.
